UNITED STATES PATENT OFFICE.

CHARLES CARR, OF BOSTON, MASSACHUSETTS.

SUSPENSION-TRACK.

SPECIFICATION forming part of Letters Patent No. 406,195, dated July 2, 1889.

Application filed July 13, 1888. Serial No. 279,869. (No model.)

To all whom it may concern:

Be it known that I, CHARLES CARR, of Boston, in the county of Suffolk and State of Massachusetts, have invented certain Improvements in Suspension or Cable Track Roads, of which the following is a specification, reference being had to the accompanying drawings, and to the letters of reference marked thereon, which comprise a part of this specification.

The nature of my invention relates to the construction of the track; and it consists of a cable provided with a sheathing of a certain construction and properly combined with and secured to the cable, all substantially as hereinafter more fully set forth and described.

With reference to the drawings, Figure 1 is a transverse section of the cable forming the main substance of the track, and showing in 20 their relative positions the cable support or bracket, the sheathing or cable-covering, and a part of a car-wheel resting in position for travel thereon. Fig. 2 is a side elevation showing the complete track, consisting of the 25 cable and its sheathing as it rests in the supporting-bracket, which is bolted to an upright post. Two lines of track are shown, one above the other. Fig. 3 shows the steel or iron plate as cut and punched ready to be bent into a 30 **U** form of section preparatory to bolting it upon the cable. Fig. 4 shows an enlarged view of one end of the same. Fig. 5 is a side view of the same after being bent into saddle or **U** form. Fig. 6 is the end view of the 35 same more perfectly bent or formed more nearly to its final shape, and indicated within are the strands of the cable in dotted circles. Fig. 7 shows the end view of the sheathing as finally bolted to the cable, the inclosed dotted 40 circles indicating, as above, the strands of the cable.

It has become quite apparent that in the adoption of wire cable as a track on which to run the wheels of cars and locomotives 45 there is a serious lack of perfect contact. This lack results in a lack of friction or grip of the locomotive driving-wheels upon the track. It also brings extraordinary wear upon certain curves of the wire which form the several strands at their upward and sidewise exposure. There is also a certain pressing and

crushing of these parts of the cable when thus imperfectly presented to the tread of the wheel. This unequal strain and wear soon abrades, injures, and even breaks the individual wires at the points referred to, and tends to destroy too early the strength and sufficiency of the cable track. 55

My invention furnishes a remedy for these evils. It proposes to guard the wires in their 60 single capacity from the injuries referred to. It proposes to utilize the strength of all the strands and all the single wires without needless extraordinary wear or strain being imposed at any individual points. It also affords 65 an excellent protection from exposure to the weather and climatic influences.

The invention serves, also, in some degree to distribute the load imposed at the point of contact of each wheel. 70

The construction is as follows: A cable is stretched in the usual methods. Sheets of metal, preferably steel or fine tenacious iron, are formed into strips, as indicated in Figs. 3 and 4. These strips are subjected to a forming process (after being punched, as shown, preferably) and made to assume a form somewhat as shown in Fig. 5. These sheets or strips of metal in the saddle or inverted-**U** form are then saddled upon the cable and are bolted 75 through their lower parts, as illustrated in Fig. 7. The bolts are screwed up to a tension which will cause the sheet-metal jacket or saddle to clamp closely about the top and sides of the cable. The ends of the strips are 80 so cut that one or more bolts shall pass through both strips or sections at each joint, thereby securing a suitable union and continuity of the several sections, as shown in Fig. 2. It will be observed that this sheet-metal covering jacket or saddle has a continuous fair bearing upon all the superficial prominences 85 of the cable, and, having a good degree of stiffness in consequence of its **U** form, serves to effectually distribute the load, which otherwise would be concentrated at the points of contact of the wheels. These sections of covering may be curved longitudinally to correspond with the sags and prominences of the cable, or may be made sufficiently light to 90 adapt themselves under the load applied in service. 95 100

I claim—

1. A continuous sheet-metal cover formed of sections united and secured to each other by bolts, in combination with a continuous cable to form a suspension-track, substantially as described.
2. The cable-track-covering sections formed with overlapping ends, in combination with holding-bolts passing through both sections, and the cable, substantially as described.
3. The cable-track covering as cut or formed with diagonal ends and bolt-holes, in combination with the cable and bolts, substantially as described.

4. A cable-track cover or jacket made continuous by means of interlocking bolts through projecting ends, in combination with the cable, substantially as described.

5. The combination of a continuous cable and a continuous sheet-metal covering formed of sections united to each other by bolts at their ends, and secured directly to the cable by means of said bolts and other transverse bolts, substantially as described.

CHARLES CARR.
